UNITED STATES PATENT OFFICE

160,253

WINDOW CLEANER

Joseph D'Angelo, Brooklyn, N. Y.

Application January 26, 1950, Serial No. 7,503

Term of patent 7 years

(Cl. D9—2)

To all whom it may concern:

Be it known that I, Joseph D'Angelo, a citizen of the United States of America, residing in Brooklyn, county of Kings, and State of New York, have invented a new, original, and ornamental Design for a Window Cleaner, of which the following is a specification, reference being had to the accompanying drawing, forming part thereof.

The figure on the drawing is a perspective view of a window cleaner showing my new design.

The rear view of the figure is substantially the same as that shown on the drawing and the dominant features of the design reside in the portions shown in solid lines.

I claim:

The ornamental design for a window cleaner, substantially as shown and described.

JOSEPH D'ANGELO.
